UNITED STATES PATENT OFFICE.

MACDOUGALD DEXTER, OF COLUMBUS, GEORGIA.

LOUVER.

Application filed October 1, 1923. Serial No. 665,928.

My invention relates to roof ventilating louvers of the class in which opposite vanes or doors are connected with the object of having the wind pressure open the lee side vane as it closes the opposite windward vane, such connection holding both vanes partly open in the absence of any unbalancing wind pressure.

I have found it desirable to hinge such vanes at their upper edges to gain the maximum effect from the wind pressure, but the pressure of ordinary winds will not act to fully close the windward vane against the increasing leverage of the lee side vane as the latter swings outwardly towards full open position.

One object of my invention is to overcome this by providing for each vane a weight which will counter-balance the vane and thus permit normal wind pressure to fully close the windward vane which is desirable to prevent the possibility of rain being blown in under such vane.

A further object of my invention is to design the vane connection as a jointed member adapted to break freely upwardly and to provide flexible connections which hang with their upper ends connected to and adapted to raise and break the connection joint and close the louver vanes when pulled, thus making it simple and easy to put the louvers into and out of service.

A further feature of my invention is the designing of the connection links so that their center joint will drop well below a plane through their connections to the vanes, thus insuring that the wind pressure will not break the joint and destroy the operating connection between the connected vanes.

A further object is to design my louvers so that they are adapted to be placed end to end to form a roof ridge or to be superimposed so as to multiply the ventilating capacity at a given point.

My invention also comprises the novel details of construction and arrangements of parts, which in their preferred embodiments only are illustrated in the accompanying drawings which form a part of this specification, and in which:—

Fig. 1 is a cross-sectional view of one form of my improved louver with the counterweights concealed under an arch dome.

Fig. 2 is a similar view of a structure with the counterweights projecting above the dome.

Fig. 3 is a side elevation on a reduced scale showing the sections of the louvers assembled to form a roof ridge.

Similar reference numerals refer to similar parts throughout the drawings.

As illustrated, the louver comprises a casing or frame formed of suitable sheet metal and comprising vertical side walls 1 and which is provided, where needed, with enclosing end walls 2. Such end walls may not be required for the intermediate sections of louver frames when assembled to form a roof ridge except to close the outer ends of the ridge. The side walls as shown in Fig. 1 are provided at their upper ends with outwardly flanges 3 which receive and support an arched dome 4 or these side walls directly support, as shown in Fig. 2, a flat-angled dome 5, according to the type of louver desired. In each side wall 1, I provide a large ventilating opening 6 and I hang from a suitable hinge 7 at the upper edge of each opening a swinging door or vane 8 which is adapted to swing by gravity to position to close the opening. The two opposite doors which are of corresponding size are connected by one or more pairs of links 9 and 10, the links 9 being hinged to one door and the links 10 to the other door, the inner ends of each pair of links 9 and 10 being pivotally connected at 11 with one of the links, 9 in the drawing, extending beyond the pivot point and being adapted to engage its connected link 10 so as to limit the breaking of the pivot joint downwardly. This stop arrangement, as shown in the drawing, will permit the pivot to drop sufficiently below a plane connecting the outer pivoted ends of the links to bring the joint below dead center and thereby to prevent pressure on either side having a tendency to break the joint upwardly. Each pair of links at its joint is connected to a flexible connection 12 which passes upwardly over a guide 13 in

the dome and then downwardly so that its lower end can be pulled by hand to accomplish the positive closing of the louver doors when desired. Obviously as the joint is broken and the links are drawn upwardly the louver doors are closed and can be held positively in this relation when ventilation is not desired.

In order that the wind pressure will act to fully close the windward door of the louver and correspondingly to fully open the lee door, I counter-balance the weight of

each door by providing one or more arms 14, which, in Fig. 1, extends upwardly into the space under the dome and carries a counterweight 15 which would tend to counter-balance the weight of the door 8. Inasmuch as the length of the links is calculated to set the doors approximately in half open position when not exposed to wind pressure, it follows that both counter-weights will 10 overhang slightly towards the center of the louver. As the windward louver door is forced inwardly the leverage of its counter-balance decreases, while the leverage of the counter-balance of the lee door increases as 15 the latter opens. The result is that the increasing leverage of the lee door itself as it swings outwardly is substantially neutralized so that the windward door is left quite sensitive to wind pressure and therefore 20 adapted to close tightly under moderate winds, which is desirable to prevent rain blowing in under the doors.

In the construction shown in Fig. 2, in order to obtain a flatter dome 5, which may 25 be desirable under certain architectural conditions, I mount the counterweights 15^a on arms 14^a which project outwardly beyond and above the side edges of the dome, and for this purpose are provided with an angled portion 16 which sufficiently offsets the upper portion of the arm to clear the overhang of the dome eaves. In Fig. 1, I have shown the counterweight 5 as an individual weight on each arm 14 of a door, but in Fig. 30 2, I have shown the counterweight 15^a as formed by a rod which extends the length of the louver and is connected to several arms 14^a of the same side of the louver.

The side walls of the louvers are provided 35 with flashing flanges 17 at their bases which serve to connect them to the roof.

In operation, having constructed and 40 mounted the louver in the manner described, upon releasing the flexible connection 12 the louver links will drop down to

operating position, setting the louver doors in normal operating position. If the links are of light material it may be desirable to attach a pull cord 18 to one of them at or near the joint so that they can be pulled 50 down to operating position. Under such conditions the ventilation takes place equally under each door as the openings 2 are equally open. When any lateral wind pressure occurs the door on the windward side will tend 55 to close and through the links correspondingly to swing the other door wider open. As the windward door swings closed its respective counterweights move in a contrary direction and their leverage decreases so that 60 the resistance of the windward door gradually decreases as its exposed area to the wind increases. On the contrary as the lee door opens its increasing leverage is counterbalanced by the increasing leverage of its 65 counterweights. It thus follows that relatively light wind pressure will close the windward doors and fully open the lee doors.

Though I have described with great particularity the details of the embodiment of 70 the invention herein shown, it is not to be construed that I am limited thereto, as changes in arrangement and substitution of equivalents may be made by those skilled in the art without departing from the invention as defined in the appended claim.

Having thus described my invention, what I claim as new and desire to secure by Letters Patent, is:—

A louver having opposite pivoted vanes, 80 a link hinged to each vane, a pivot connecting the adjacent ends of said links, means to hold said links with their pivot below dead center position, said means comprising a positive stop on the links, and an overhead 85 flexible connection adapted to break said pivot joint and draw the louver vanes closed.

In testimony whereof I affix my signature.

MacDOUGALD DEXTER.
